HEAT EXCHANGER

James Fletcher, Akron, Ohio, assignor to The Babcock & Wilcox Company, Newark, N. J., a corporation of New Jersey

Application August 1, 1939, Serial No. 287,702

6 Claims. (Cl. 122—365)

This invention relates to heat exchange apparatus of the vapor generating class and it is particularly concerned with tubular connections through which a liquid or fluid is introduced to pressure vessels employed in such apparatus. Certain types of vapor generators and steam boilers require the use of pressure vessels such as steel drums and headers arranged with metallic tubular conduits connected to them in a pressure-tight manner, and such arrangements usually involve thermal connections between these elements, and when the liquid or fluid flowing through such connections to the pressure vessel is at a temperature substantially different from the vapor or liquid contents of the drum, the metallic elements of the connections transfer heat between the fluid in the tubular connections and the drum walls. If the liquid in such connections is at a temperature substantially below the temperature of the contents of the drum, this transfer of heat because of the temperature differential, may cause the cooling of the drum metal in the zone of the connection to considerable extent below the temperature of the vapor within the drum. When such a reduction in drum wall temperature occurs at the connection while the steel drum wall is maintained at the temperature of the drum contents at adjacent positions a condition occurs wherein high stresses are produced in the drum wall. When such conditions are long continued cracks may appear in the drum metal, weakening that structure and necessitating extensive repairs, and such results are often aggravated when the fluid is such that it has a corrosive effect upon the metal.

In pressure vessels of the character referred to, for high pressure, for instance, above 600 lbs. per sq. in., the walls are of metal of high tensile strength and of substantial thickness, even when of moderate diameter, and of equal thickness for lower pressure and larger drum diameter. Tubes or connections are required to supply fluid to, or withdraw it from, such pressure vessels in service, and the fluid flowing through such connections may have substantially lower or higher temperature than that contained in the pressure vessel.

The temperature of the metal of the pressure vessel is normally that of the fluid contained in it, especially when there is external insulation, and the temperature of the metal of the tube or pipe conveying fluid to, through, or from the vessel is the same as that of the fluid flowing in it, or very nearly so. The metal of the connecting tube and that of the vessel walls are in contact

at a junction which, in high pressure work, is a joint that is rolled or welded, and the metal of the tube may extend wholly through the hole in the vessel wall. When the tube does not extend entirely through the hole, the flowing fluid will come into direct contact with the metal of the wall of the pressure vessel and tend to give it the fluid temperature at the contact surface, unless means are provided to prevent such contact.

When the flowing fluid has a different temperature than that of the fluid in the vessel steadily or momentarily, the tube metal in contact with the flowing fluid will have a different temperature than the metal of the vessel wall, and the metal of higher temperature will have expanded more than the other. This relative expansion will have an undesirable effect on the joint between the two metal parts. For example, if the tube is steadily conveying a fluid to the vessel and the flowing fluid is colder than the main body of fluid within the vessel, the tube metal will contract relative to that of the vessel and damage to the connection will result. A tube expanded into a hole in the vessel wall will act this way. In such a joint, and under these steady conditions, there will be a flow of heat from the hotter metal of the vessel wall to the colder metal of the tube in contact with it, so that the metal of the tube at this zone will not be as cold as the fluid flowing inside of it. However, if the fluid entering through the tube suddenly becomes colder than that in the vessel, especially if, at the same time, its flow rate also increases, then the tube metal will suddenly cool and contract because of lack of time for heat flow from the vessel wall to the tube metal to compensate, and leaky conditions will result. Such leaky conditions with high pressure fluid will increase and may become permanent because of the erosive effect of such escaping fluid on the surrounding metal.

In addition to the bad effect on joints between tube and vessel metal arising from different fluid temperatures, especially when there is a sudden change in that of the flowing fluid, there is another type of undesirable effect that may result and this is an excessive stress in the metal of the vessel that may cause a crack or a rupture. An example of such a condition arises when the fluid entering the vessel is much hotter or much colder than the fluid in the vessel so that there is a temperature gradient and a heat flow in the metal of the vessel wall around the tube hole radially away from the hole, or toward it. When

the metal of the vessel wall is colder at the tube seat than at a distance from it, the metal at the tube seat is contracted relative to that at a distance, and thus a tension stress is set up, more severe, the greater the radial temperature gradient; that is, the greater the temperature difference per inch of distance. Such a tension stress may exceed the resistance of the metal and produce a crack. Contrariwise as to temperature difference, a higher temperature in the flowing fluid will cause the metal of the vessel wall to expand at the tube seat relative to the metal at a distance, and a crushing stress will be set up, which may exceed the metal resistance, and cause a failure of the joint between the tubular connection and the drum.

Such stresses beyond the elastic limit of the metal are serious, and may be more serious than the leaks due to relative expansion of the two metals at a joint. Some joints between the metal of the tube and that of the vessel wall are of the metallically integral type produced, for example, by fusion welding. Relative expansion of the two metals thus joined may result in an excessive stress in the junction metal and cause the joint to fail, independent of damage to the metal of the vessel wall or that of the tube. Such failures are doubly serious as to the operativeness and safety of such structures.

When such tubular connections supply feedwater to the steam and water drum of a high pressure steam boiler and extend through the steam space of the drum, there exists a set of conditions particularly favorable to the production of the above indicated undesirable results. This is particularly true when the metal is highly stressed and simultaneously exposed to pure condensate.

When the operating characteristics of the vapor generator of which the illustrative tubular sections are parts involve wide changes in temperature of the liquid flowing through such connections, in short periods of time, and intermittent heating and cooling of the metal in the zone of the tubular connection, there will be resultant over-stressing of the metal, and fatigue failure due to intermittent stressing may occur more quickly than when operating conditions are steady.

This invention solves such problems by affording tubular connections which are particularly applicable to high pressure boilers wherein the feed from an economizer to the steam and water drum of the boiler varies widely in temperature due to operating conditions beyond the control of the designer.

The problem of supplying safer equipment for the foregoing conditions of service is solved in the present instance by a construction which minimizes the damaging temperature differentials and thus accomplishes a controlled relative expansion and contraction such as to materially reduce the liability of leakage or cracking due to stresses and in most cases to entirely prevent leakage and failure of the metal.

Other objects of the invention will appear as the accompanying description proceeds.

The invention will be described with reference to preferred embodiments which are indicated in the accompanying drawings.

In the drawings.

Fig. 1 is a vertical section of a vapor generator operating at high pressures and high temperatures;

Fig. 2 is a vertical section of a part of the high

pressure steam and water drum included in the Fig. 1 installation, with an embodiment of the invention associated therewith;

Fig. 3 is a transverse section of the tubular drum connection indicated in Fig. 2, this section being taken on the line 3-3 of Fig. 2 and looking in the direction of the arrows. This view particularly shows means whereby the ferrule is held spaced internally from, and centered with respect to, the drum connected tube;

Fig. 4 is a vertical section through a drum and tube connection adapted for operation with a steam generator operating at pressures in excess of 2000 lb. per sq. in.; and

Fig. 5 is a transverse section through the throttle ring of the Fig. 4 embodiment, this section being taken on the line 5-5 of Fig. 4 and looking in the direction of the arrows.

Fig. 1 of the drawings indicates a steam generating installation in which feedwater from the economizer 10 passes through the conduits 11 and 12 to a steam and water drum 14. This particular installation operates at steam pressures in excess of 2000 lb. per sq. in., and, consequently, the drum must have thick walls and be constructed of steel of high quality. The particular drum 14 has a diameter in excess of 5 ft. and has walls of a thickness in excess of 6½ in. The steam in the drum has a saturated temperature of about 650° F.

The conduits 11 and 12 conduct the discharge from the economizer 10 to the drum 14, and they enter the steam space of the drum downwardly as indicated in Fig. 1. Each of these conduits 15 may be connected with an internal feed pipe which conducts the entire flow of fluid through the tubes to a feedwater distributor located at another position in the drum, and the preferable arrangement is that such internal ferrules as those indicated at 24 and 108 in Figs. 2 and 4 shall be directly connected with such internal feed pipes.

A tubular drum connection by which one of the conduits 11 or 12 communicates with an internal feed pipe is particularly indicated in the drawings. As shown in Fig. 2 the conduit 11 is welded to an external sleeve or tubular connection 20. The latter forms a continuation of the conduit 11 and extends through an opening 22 in the drum wall 26. The major portion of the tube opening is slightly larger than the external diameter of the tubular member 20, and the positive connection between the drum metal and the metal of the member 20 is limited to the inner part of the drum wall. The inner end of the tubular member 20 when in assembled position may have tube metal extending into the grooves 28 and 30 formed within the tube seat.

The inner end of the tubular member 20, forming in effect the end of the conduit 11, is tightly expanded against the tube seat. The extreme inner end of the tubular member 20 is then slightly belled out as indicated at 32 and is thereafter preferably seal welded to the inner face of the drum wall by the deposition of weld metal indicated at 34.

The ferrule 24 has an external diameter which is less than the internal diameter of the tubular member 20 and it is formed integrally with a circumferential collar 36 at its end disposed externally of the drum. Between this circumferential collar 36 and the inner end of the ferrule 24, the latter is formed with another integral annular collar, or throttle ring, 40.

The outside diameters of the circumferential collar 36 and the major part of the outside sur-

face of the throttle ring 40 are such that the entire ferrule assembly may be moved within the tubular member 20 to the position indicated in Fig. 2 of the drawings, and the circumferentially arranged spacers 42 near the lower end of the ferrule are also formed to permit this action. After the ferrule 24 is inserted within the tubular member 20 and brought to the position indicated in Fig. 2 of the drawings, it is expanded against the inner surface of the member 30 at the position of the collar 36 and the throttle ring 40. There are thus formed two annular chambers 42 and 44, within the member 20 and between it and the outside surface of the ferrule 24. These chambers are separated by the throttle ring 40 which has the same relation to the surfaces of the ferrule 24 and the member 20 as the throttle ring 102 has to the member 100 and the ferrule 108 in Fig. 5 of the drawings.

The upper part of the throttle ring 40 is provided with a steam inlet similar to the opening 120 shown in Fig. 5, and a drain opening of a greater circumferential extent is provided at the lower part of the throttle ring. This drain opening 46 corresponds with the opening 124 of the throttle ring construction indicated in Fig. 5, and the steam inlet opening 48 corresponds to the opening 120. As the tube 20 enters the drum in an upper quadrant above the normal water line of the drum which is at or slightly below the centerline, the annular chambers 42 and 44 are in communication with the steam space of the drum 14. The two integral collars 36 and 40 which are expanded into the tube 20 in order to position the ferrule 24 in proper position in the tube also effect a good thermal bond in the cylindrical zone of contact. This permits a limited transfer of heat from the ferrule 24 to the tube 20 at the position of the collars 36 and 40.

The throttle rings separate the annular spaces between the outer tubes and their respective ferrules into two longitudinally adjacent chambers which, because of their different positions with respect to the vapor space of the drum (which is the source of heat when the invention is embodied in a steam boiler), will operate with different temperature conditions. The temperature of the tube 20 in the length between the collar 36 and the tube seat will be maintained at a value intermediate the drum temperature and the temperature of the fluid flowing through the drum with the temperature change gradual from end to end of the gradient.

In either embodiment of the invention the throttle ring positioned intermediate the ends of the ferrule inside of the tube (either 20 or 100) divides the annular space between the ferrule and the tube and is effective to prevent too steep a temperature gradient at the zone of junction between the ferrule and the tube around it. With the use of the throttle ring the temperature gradient is more gradual, and it extends from a position adjacent the throttle ring to a position adjacent the zone of junction between the ferrule and its external tube.

The arcuate ports 120 and 124, in the upper and lower quadrants of the collars, provide for the controlled movement of steam, or vapor, to the outside chambers 42 and 122. They also provide for the controlled draining of condensate formed in these annular chambers, while still transferring some heat between the inner wall of the tube 20 or the tube 100 and the inner wall of the ferrule 24 or 108.

An increase in flow area of the arcuate open-

ings 120 and 124 will permit greater freedom of flow of heating vapor into the outside annular chamber with a subsequent tendency to produce a steeper temperature gradient.

5 The extent of thermal contact of the expanded throttle ring with the interior wall of the outer tube effects the transfer of heat by conduction between the inner and outer tube of the ferrule and this transfer tends to counteract the temperature of the annular chamber.

When tubular connections such as those above described enter a drum radially above its horizontal centerline the cooled liquid in the annular space between the ferrule and the tube externally thereof can drain into the drum. This permits controlled circulation of the high temperature medium into the high annulus, replacing the cooled liquid drained from the annulus. When, as in the embodiments shown in the drawings, the tubular connections are in the steam space of a steam and water drum the circulation between the annular chamber and the steam space will be more rapid. This natural circulation maintains practically the full internal drum temperature over the entire length of the annulus when no throttle ring is employed and this results in a very steep temperature gradient across the ring section forming the junction between the ferrule and outer tubes at the end of the annular chamber remote from the drum.

With such tubular connections as those shown and described herein, the most satisfactory condition is to maintain the temperature of the medium in the annular chamber between the ferrule and its surrounding tube at a value approximately the same as the temperature of the internal medium in the drum for distances within the annular chamber equal to the length or width of the contact area between the outer tube and the drum metal. From this position in the annular chamber to its end remote from the drum, or to the position of the juncture between the inner or outer tubes, the temperature of the medium between the inner and outer tubes should follow a gradient from feedwater temperature at the end of the annular chamber remote from the drum to drum wall temperature at the point of first contact between the outer tube and the tube seat.

50 As the port 120 restricts and controls the vapor into the chamber 122 and the port 124 controls the drainage of condensate therefrom, the pressure of the vapor in the chamber 122 will be less than that of the annular chamber 126, and less than the pressure within the drum. This pressure differential will depend upon the frictional resistance of the port 120 to the flow of vapor introduced by condensation in the chamber 122, and the rate of condensation is determined by the temperature of the fluid flowing through the tube 100 or the end of the ferrule 108.

When the temperature differential between the fluid of the tube 100 and the fluid within the drum is greatest, the pressure in the chamber 122 will be at a minimum. The vapor temperature of the chamber 122 will be uniform throughout its length and will depend upon the pressure.

With the illustrative arrangement the ferrule 108 is subject to vapor heating on its outside surface, and the inside surface of the tube 100 in its length corresponding to the length of the ferrule 108 therein is also subject to such heating. The temperature of the vapor in the annular chamber 126 corresponds to that of the drum while that of the chamber 122 is lower.

The embodiment of the invention indicated in Figs. 4 and 5 of the drawings includes a feed-water tube 100 the inner end of which is expanded against the inner part of a tube seat formed in the drum wall 102. The tube 100 preferably enters the drum radially and at about an angle of 45° above the centerline of the drum. After the tube is expanded within the drum its inner end is preferably belled out as indicated at 104. It is also seal welded to the drum wall as indicated at 106.

Telescoped within the tube 100 and extending beyond the tube into the drum wall 102 there is a ferrule 108. This ferrule is provided at its outer end with an integral collar or boss 110 and at a position intermediate its length, it is provided with another external collar or throttle ring 112. Each of these collars fits tightly within the tube 100 and is secured to the tube by expanding operations with the ferrule. The throttle ring may have been previously fixed to the ferrule 108 by an expanding operation performed before the ferrule assembly is inserted within the tube 100.

The ferrule 108, at its inner end, is in free contact with the high temperature fluid within the drum and at positions spaced from the drum it is in good heat transfer relationship with the tube 100.

At the top of the collar 112 there is a small opening 120 providing a restricted passage for steam to the annular chamber 142. Any steam condensing in this chamber by reason of the cooling action of the low temperature fluid flowing through the ferrule 108, drains from this chamber through the arcuate drain opening 124, indicated in Fig. 5 of the drawings.

The ferrule 108, in conjunction with the tube 100 and the collars 110 and 112, forms the two annular chambers 122 and 126 the latter of which is in free communication with the fluid within the drum 102. The action of the high temperature fluid circulating through these annular chambers combines with the conduction of heat through the metal of the ferrule 108 and its collars 110 and 112 to transfer heat from the high temperature fluid in the drum to the metal of the tube 100 at such rates that the temperature curves indicated by the temperature diagram of Fig. 4 apply. The curves of this diagram indicate the metal temperatures along a section of the tube 100 within the influence of the heat transfer affected by the ferrule construction and the fluid action associated therewith. These curves represent the results of experimental tests. During the tests the temperature of the fluid within the tube 100 was approximately 75° F., and consequently the curves start at this temperature, at a point on the tube 100 about 7" removed from the drum wall 102, and the action of the various heat transfer influences above described, results in the gradual increase in the temperature of the tube 100 as the wall of the drum is approached. For example, an upper curve shows that the temperature of the tube 100 at a point 3" away from the drum wall is about 300° F., and from that point there is a rise in the temperature of the tube metal until at the drum wall the tube metal has reached the saturation temperature within the drum, approximately 412° F. Consequently, at a position adjacent the tube seat there is no drum metal temperature differential of sufficient extent to cause any damaging stresses across the wall of the drum at the tube seat. The lower set of curves of the thermal diagram of Fig. 4 indicates the origi-

nal temperature of the metal of the tube 100 as being about 75° F. at a position 7" removed from the drum wall 102, and the temperature for both the bottom and the top of the tube gradually rises as the drum wall is approached. It rises to the saturation temperature of another set of operating conditions, that temperature being in this case slightly over 300° F.

With further reference to the embodiment of the invention indicated in Fig. 4 of the drawings, it is also to be noted that the tube 100 has a pressure-tight relation with the metal of the drum wall 102 over only a fraction of the thickness of the wall. Such relationship extends from the seal weld 106 to a position indicated by the reference character A, and from A to B the tube 100 may be considered as loosely fitting within the opening of the drum wall. This relationship prevents loosening of the tube seat due to "creeping" which might occur if the expanded tube seat connection between the tube and the drum extended over the entire thickness of the drum wall.

Referring again to Fig. 1 of the drawings, the economizer 10 is subject to contact with gases from the furnace 130. As shown, this furnace is fired by a plurality of pulverized fuel burners 132, 134, and 136, and the gases pass from the furnace through an exit 138 to the bottom of the gas pass 140 in which the economizer 10 is located. The gases flow directly upwardly through this gas pass and through a flue 141 in which one or more dampers 142 are located.

The furnace 130 is defined by water tubes connected into the boiler circulation. Some of these tubes 144 and 146 extend directly downwardly from the drum 14 to the header 148. Roof tubes 150 extend from the drum 14 to the header 152 which is connected with the lower header 154 by the upright wall tubes 156. From the header 154 the floor tubes 158 extend at a downward inclination to the header 160. Suitable downcomer connections establish communication between the water space of the drum 14 and the headers 148 and 160, and in the present instance, some of these downcomers include the tubes 164 and 166 which extend across the path of the gases in the gas pass 140 and then downwardly alongside the wall 170 to the header 148. The side walls of the furnace may be defined by upright tubes directly connecting the headers 180 and 190 which have appropriate circulatory connections with the drum 14.

I claim:

1. In combination, a steam and water drum, a tube directly communicating with the steam space of the drum for the flow of a fluid at a temperature differing materially from the temperature of a fluid within the drum, means within the tube and extending past the junction of the tube and the drum to provide an annular chamber directly communicating with the interior of the drum, and an annular restrictor disposed transversely of said chamber to divide it into two shorter chambers and provided with a restricted opening to limit circulation of steam and water between the drum and said chamber.

2. In a steam boiler, a steam and water drum, economizer tubes entering the drum and expanded into the shell thereof, an auxiliary tube in each of said economizer tubes and extending from a point outside of said shell into said drum, said auxiliary tube being spaced from the interior of its economizer tube at the expanded portion thereof and arranged to conduct the water flow-

ing through said economizer tube into said drum and maintain the water out of thermal contact with said expanded portion, and a throttle ring fixed around the auxiliary tube intermediate its ends so as to divide the annular space between each economizer tube and its auxiliary tube into a plurality of connected fluid chambers in communication with said drum.

3. In a fluid heat exchange system, a pressure vessel for a fluid at one temperature, a tube fixed within an opening in the wall of the pressure vessel and functioning to conduct to the vessel a fluid at a temperature considerably different from the temperature of the fluid within the vessel, and a tubular member fixed within the tube and having its outer surface spaced from the inner surface of the tube, said tubular member having a plurality of external annular collars in tight metal-to-metal contact with the member and the inner surface of said tube with one of the collars positioned at the end of the tubular member outside of the vessel and a second positioned intermediate the ends of the tubular member but within the tube and spaced from the end thereof, the second collar dividing the annular space between said tubular member and the tube into two component annular chambers in communication through an opening provided in said collar, the inner end of the tubular member extending to a position within the pressure vessel where its external surface is in free contact with the fluid within the vessel.

4. A thermal gradient tubular connection for fluid heat exchange apparatus comprising a thick walled pressure vessel, a tubular member communicating directly with the vessel, fluid flowing through said member to the vessel being at times at temperatures considerably lower than the temperature of the fluid within the vessel, and a thermal gradient ferrule secured within said member and spaced therefrom to afford an an-

nular chamber in communication with the fluid within the vessel, and a second annular chamber in restricted communication with the first, the ferrule being provided with a throttle ring separating said chambers.

5. In a water tube steam boiler, a steam and water drum, an economizer, an economizer outlet tube in communication with the steam space of the drum and conducting fluid into the drum at temperatures materially less than the temperature of the fluid within the drum, and thermal gradient ferrule means including an inner tube with spaced collars fixed thereon and in metal-to-metal contact with the inner wall of the economizer outlet tube in distinct and separated circular zones both of which are disposed externally of the drum wall, said means establishing such a thermal gradient in a section of the economizer outlet tube adjacent the drum that the metal of this section closely approaches the temperature of the fluid within the drum.

6. In a fluid heat exchange installation; a pressure vessel; and a thermal gradient tubular connection in communication with the vessel; the tubular connection including two concentric conduits with the conduit of smaller diameter extending through an opening in the wall of the vessel, said conduit being subject to the flow into the vessel of a fluid at a temperature materially differing from the temperature of fluid within the vessel, the outer conduit secured to the vessel in pressure tight relationship and extending externally thereof at least to a position wherein it is secured to the inner conduit, and ring means contacting said conduits and disposed transversely of the annular space between them, said ring means being located between said position and said pressure tight connection and dividing the annular space between said conduits into two distinctive temperature zones.

JAMES FLETCHER.
